Design No 563. -

James L. Jackson Grateframe & Summerpiece

Patented 3rd May 1853.

James L. Jackson, of New York, N. Y. **DES 563**
Letters Patent No. 563. Dated May 3^d, 1853.

The schedule referred to in these Letters Patent and making part of the same.

To all whom it may concern:

Be it known that I, James L. Jackson, of the city, County and State of New York, have invented or produced, a new and original design for a Grate-frame and Summerpiece, and I do hereby declare the following, to be a full, clear, and exact description of the same reference being had to the accompanying drawing making a part thereof, and which represents one half of the grate frame and summer piece complete, the other half which is the same precisely in configuration, being shown in outline only, and representing by a sectional line the projection of the mouldings and other parts.

The general outline of the frame is square, the upper corners of the opening for the summer pieces being slightly rounded. The top centre piece a, of the frame, is formed with highly raised leaves and foliated scroll work terminating in a vine, the whole being in a sunken panel. A sunken panel b, is made in about the middle of the frame, and extending clear round from the centre piece to the base c, of the jamb, with but the single ornament d. Both sides of this panel is margined by delicate mouldings e, raised. The corner ornament is formed of a "Thyrsus" f, with volutes g, entwined around it, from which spring out vines with foliage and fruit, extending a short distance along the top of the frame, and farther down its sides. This ornament is also in a sunken panel, margined by a delicate bead around the edge of the frame. A narrow but abrupt cavetto moulding h, with a delicate bead i, throws the inner portion of the frame far back, so as afford more relief to the ornaments.

The summerpiece is intended to fit the opening in the frame, and has a sunken semi-circular top panel in the centre, in which is placed resting on its base, an urn j, highly wrought, with foliated scroll work extending from top to bottom forming handles. A frame k, rises out of the urn, and the ground is openwork. Outside of the panel in which the urn and its ornaments are placed, is a parallelogram k', and in the spandrel formed by it and the semi-circular top of the

Des 563

panel, is foliated scroll work l, enclosing a flower m, in its volute, from which hangs a bunch of grapes n, terminating in a vine. Outside of the parallelogram is a voluted vine o, with foliage. The entire ground of the summer piece where ornamented, is in open work.

The shaded lines x, represents a section through the plates showing the relative positions of the projecting portions thereof.

Having thus fully described the nature of my invention what I claim therein as new and desire to secure by Letters Patent, is the combination and arrangement of the figures, flowers & ornaments herein represented, the whole forming an ornamental design for a grate frame and summer piece.
